UNITED STATES PATENT OFFICE.

CHARLES HAINES WILLIAMS, OF CHICAGO, ILLINOIS, ASSIGNOR TO CHICAGO RAILWAY EQUIPMENT COMPANY, OF CHICAGO, ILLINOIS, A CORPORATION OF ILLINOIS.

BRAKE-BEAM SUSPENSION.

1,255,967.

Specification of Letters Patent. Patented Feb. 12, 1918.

Application filed February 14, 1917. Serial No. 148,552.

To all whom it may concern:

Be it known that I, CHARLES HAINES WILLIAMS, a citizen of the United States, residing at the city of Chicago, county of Cook, 5 and State of Illinois, have invented a certain new and useful Improvement in Brake-Beam Suspensions, of which the following is a full, clear, and exact description, such as will enable others skilled in the art to 10 which it appertains to make and use the same, reference being had to the accompanying drawings, forming part of this specification.

This invention relates generally to the 15 brake gear of railway trucks, and specifically to certain improvements in the manner of supporting the brake beam for coöperation with the truck wheels in the normal braking operations.

20 The specific objects of the present improvements are, to provide an arrangement whereby a positive and definitely directed spring pressure may be employed to effect the desired release or throwing off of the 25 brakes from the wheels when the pressure is removed from the brake operating mechanism, and to afford at the same time the proper guide and support for the brake beam commonly called the third or fourth 30 point support.

Other objects will be obvious or pointed out hereinafter, reference being had to the accompanying drawings, in which—

Figure 1 represents a detail of truck 35 equipment showing portions embodying my invention in elevation and certain parts in vertical section;

Fig. 2 is a top or plan view of the same mechanism;

40 Fig. 3 is a detail of a modified form showing parts in elevation and vertical section;

Figs. 4, 5, 6 and 7 are similar details showing respectively other modified embodiments of the invention;

45 Fig. 8 is a top or plan view of the portions shown in Fig. 7;

Fig. 9 is a detail of still another modified embodiment showing parts in side elevation and vertical section.

50 As is well known in the art, the brakes in railway rolling stock are customarily set by mechanism operated by air pressure, and the removal or throwing off of the brakes is designed to be accomplished by the release

spring forming a part of the air brake mechanism. The extent to which the latter operation is accomplished, however, depends very largely upon the condition of the equipment, and a circumstance frequently encountered is a failure of the brakes to be completely removed from the wheels, thus increasing the train resistance and the wear on the equipment.

Various arrangements of springs in association with the brake beam have been made 65 with the intention of throwing off the brakes by spring pressure applied to the beam. With such arrangements a difficulty has been encountered in maintaining the proper alinement and position of the brake shoes 70 while the movement of the brake beam, in the application of the brakes, is storing in the spring the energy which is intended subsequently to release or throw off the brakes.

By the arrangements herein illustrated 75 and about to be described, I provide the necessary spring pressure for effecting the complete release of the brakes, and at the same time afford the brake beam the proper guidance and support to insure its proper manipulation and the proper application of the 80 shoes to the wheels.

Referring to the drawings in detail by means of the reference characters applied, let it be understood that the numeral 1 designates the spring plank of the truck; 2 the compression member of the brake beam; 4 the tension member thereof; 5 the brake beam strut; and 6 the brake head, all of 85 which parts may be arranged in the conventional fashion.

Affixed to the spring plank 1 so as to extend transversely below the brake beam, is the supporting member 7, which may be in the form of a rigid bar carrying a resilient guiding member 7^a, as illustrated in Figs. 1, 2, 3 and 9, a resilient member as illustrated in Figs. 7 and 8, or a rigid member without the resilient portion as illustrated in Figs. 4, 5 and 6. Suitable means 95 for affording a third point of support for the brake beam is provided and comprises an arrangement such as the shoe 8 illustrated in Figs. 1 to 4 inclusive and 7 to 9 inclusive, which shoe is designed to coöperate with some portion of the supporting member 7 to give the brake beam the proper support and guidance at the tension side,

2

or said third point support may be in some other form such as the link 8' illustrated in Figs. 5 and 6, said link being attached to a truck portion at its upper end to provide 5 the desired suspension and guidance for the beam. In association with the beam and the supporting member 7, I dispose a yielding pressure means 10, the essential arrangement of which is that it be placed 10 under compression or tension by the movement of the brake beam in the operation of applying the brakes, and that its line of reaction be in such direction with reference to the brake beam as to urge the latter for 15 the proper movement to release or throw off the brakes from coöperation with the wheels. A third essential in the arrangement of the yielding pressure means 10, is that it be so disposed as not to throw the 20 beam out of proper alinement and elevation during the operation of applying the brakes, which proper alinement and elevation it is the purpose of the third and fourth point supports to maintain. Accordingly, 25 in the forms wherein the sliding third or fourth point support is employed, such as is illustrated in Figs. 1 to 4 inclusive and 7 to 9 inclusive, it is desirable that the arrangement of the yielding pressure means 30 10 be such as to hold the shoes 8 in engagement with the sloping guideway on the supporting member 7, and in the forms illustrated in Figs. 5 and 6, wherein the brake beam has an oscillatory movement, it 35 is desirable that the yielding pressure means have the proper flexibility in a vertical direction to accommodate the rising movement of the beam. Furthermore, it is of importance that the line of reaction of 40 the yielding pressure means 10 be in alinement transversely of the beam with the third or fourth point support. Consequently, to fulfil these requirements, I dispose the yielding pressure means 10 in the 45 forms illustrated in Figs. 1 to 4 inclusive and 7 to 9 inclusive, on the line of movement followed by the forward or tension side of the brake beam in the movement thereof during the application of the brakes, 50 and so that the resultant of the moment of the brake beam in this operation and the reaction of the yielding pressure means, intersects the path of travel of the supporting shoe 8. In the form illustrated in Fig. 55 5, the yielding pressure means 10 is given the proper vertical flexibility by a loose mounting on the supporting member 7 through the guide rod 11 and slot 12, and in the form illustrated in Fig. 6 by the 60 length and convoluted form of the flat spring which comprises the yielding pressure means 10.

It will be observed that, while in the forms illustrated in Figs. 1 to 6 inclusive 65 the improvement is disposed in cooperation

with a third point support, in the forms illustrated in Figs. 7 to 9 inclusive it is arranged in coöperation with a fourth point support.

It is believed that the operation of the device is obvious. Upon application of the brakes, energy is stored in the yielding pressure means 10 by movement of the brake beam, while the arrangement and reaction of the yielding pressure means are such as 75 to permit the proper movement of the tension side of the beam, and in fact to contribute to the proper guidance thereof by the third or fourth point supporting arrangement. Upon release of the brakes, the 80 reaction of the yielding pressure means is exerted upon the brake beam in definite direction to give it positive actuation and insure the release of the brakes and the removal of the shoes from the wheels. 85

Obviously changes and modifications in the embodiment of my invention may be made other than those herein illustrated and described, without departing from the scope of the appended claims. 90

What I claim is:

1. In a truck, a brake beam suspension including a supporting member affixed to a truck portion, a third or fourth point support for guiding the brake beam in operative movements thereof, and a yielding pressure means disposed in association with the brake beam and said supporting member in the line of movement of the third or fourth point support to derive energy from the 95 movement of the brake beam in the application of the brakes and to react upon the brake beam to effect the release of the brakes when the operating pressure is removed. 100

2. In a brake beam suspension, the combination of a supporting member carried by a portion of the truck in association with the brake beam, a third or fourth point supporting arrangement for guiding the brake beam in braking movements, and a yielding pressure means carried on the supporting member and arranged for coöperation with the brake beam substantially in the line of operative movement thereof. 110

3. In a truck, the combination of a brake 115 beam, a supporting member carried by a portion of the truck and extending below the beam, a third or fourth point supporting device for guiding the beam in braking movements, and yielding pressure means 120 carried by the supporting member and associated with the beam to exert pressure upon the same to release the brakes.

4. In a truck, the combination of a brake beam supported for oscillatory movement, a 125 supporting member carried by a truck portion and extending transversely below the beam, a portion connected with said supporting member for guiding the brake beam in braking movements, and yielding pressure 130

means carried by the supporting member and coöperating with the brake beam to urge the same to release the brakes.

5. In a truck, the combination of a brake beam, a supporting member carried by a truck portion in association with the beam, a portion carried by said supporting member for coöperation with the beam to guide the same for tilting movement in braking operations, and yielding pressure means carried by the supporting member and associated with the beam to maintain the same in coöperation with said guiding portion and to urge the beam to release the brakes.
10. 6. In a truck, the combination of a brake beam, a supporting member carried by a

truck portion in association with the beam, a guiding portion on the supporting member for affording a third or fourth point support for the beam, and yielding pressure means carried by the supporting member and associated with the beam for effective coöperation therewith substantially on a line transversely of the beam with the third or fourth point supporting arrangement. 20

In testimony whereof I hereunto affix my signature in the presence of two witnesses, this 9th day of February, 1917.

CHARLES HAINES WILLIAMS.
